UNITED STATES PATENT OFFICE.

JULIUS COHEN, OF MANCHESTER, ENGLAND.

PORTABLE AND FOLDING DESK, REST, OR THE LIKE AND MEANS FOR SUPPORTING THE SAME.

1,111,524.

Specification of Letters Patent.

Patented Sept. 22, 1914.

Application filed November 25, 1913. Serial No. 802,895.

To all whom it may concern:

Be it known that I, JULIUS COHEN, a subject of the King of Great Britain and Ireland, residing at 4 Aytown street, Manchester, 5 in the county of Lancaster, England, have invented new and useful Improvements in Portable and Folding Desks, Rests, or the like and Means for Supporting the Same, of which the following is a specification.

10 This invention relates to an improved portable and collapsible desk, rest, support, or the like, which is of extremely compact form and yet when opened out and supported in the manner to be described is rigid and 15 effective for the purposes in view.

The object of my invention is to provide a very neat, and preferably foldable desk or rest, which, while being capable of folding substantially flat can yet be readily opened 20 out and sustained in opened out condition using an umbrella, walking stick, or a stick or stand for that purpose.

Thus a device is produced by which a reader can have a book supported (with 25 great comfort to himself) on the desk, one hand being sufficient to hold the umbrella or the like vertical and the desk in position, while the other hand is left entirely free.

I utilize according to my invention an 30 umbrella, walking stick, or other stick, or stand, to support a folding desk or the like and I make the desk in manner to combine with the umbrella or walking stick handle or other stand and to be slung therefrom or supported thereby. The desk or rest may 35 be carried by a suitable stand.

As a modification, the desk or rest when apart from its stand need not necessarily fold.

40 In the following detailed description I describe various forms of desk or rest device according to my invention and also several types of stand for the same and the description will be easily understood when read in 45 connection with the attached three sheets of drawings, wherein:—

Figure 1 shows an end elevation of one 50 form of collapsible desk or rest as when supported on a walking stick or umbrella handle. Fig. 2 is a plan of Fig. 1. Fig. 3 illustrates the same desk or rest in front elevation and when opened out. Fig. 4 shows a slightly modified form of desk or 55 rest device in rear elevation and in position supported on an umbrella handle. Fig. 5 is

a plan of the device shown by Fig. 4 but in a collapsed condition. Fig. 6 illustrates the same desk or rest device seen in Figs. 4 and 5 but shows the same in front elevation and supported on a stick or umbrella handle. 60 Fig. 7 shows a slightly modified form of collapsible desk or rest device in opened out condition and in position on an umbrella handle, and, Fig. 8 is a plan of the desk or rest device collapsed or folded. Fig. 8^a is a 65 detail view to be examined with Fig. 8. Fig. 9 shows another form of collapsible desk or rest in back view and supported on a provided stand, the stand &c. being broken in length. Fig. 10 is a plan view of Fig. 9. 70 Fig. 11 illustrates another form of my collapsible desk or rest and as supported on a provided stand broken in length for want of room in the drawing. Fig. 12 shows a broken plan of Fig. 11. Fig. 13 indicates 75 in elevation another form of desk or rest for use with a stand, the halves of the desk or rest in this case not folding. Fig. 14 is a plan view of Fig. 13.

In constructing desks or rests according to 80 my invention, and, by way of the first example shown by Figs. 1 to 3, I hinge or connect together two flat boards such as the boards *a* and *b* hinged at *c*. The boards may be laminated boards of wood and are so 85 hinged or connected that the board *b* can open upward with respect to the board *a* and assume a position at right-angles thereto, or fold more or less to the board *a* for packing-up and transport (see the dotted 90 lines Fig. 1). Obviously I may make the sections *a* and *b* from any suitable material. To the board *a* I for preference attach or 95 hinge a ledge or abutments and in Figs. 1 to 3 this ledge *d* is shown attached to the board *a*. Fingers *e* pivoted at *e'* are preferably applied to the ledge *d* and may be folded out of the way as shown in dotted line Fig. 2, or turned-up to hold down the leaves of a book as is illustrated in Fig. 1. 100 A second strip *f* is preferably applied to the board *a* and this may be fixed or adjustable and its use enables me to vary the angle at which a book or the like is held when the desk is in use, that is, the book may rest 105 against the ledge *d* or against the strip *f* as desired. The strip *f* also occupies a slot *f'* formed in the back board *b* when same is folded down, and, the turn-button *f''* serves to hold the back board *b* in the folded posi- 110

tion so that with the fingers *e* turned to the position shown in dotted lines in Fig. 2 the rest is entirely compact and ready for the pocket.

To the outer face of the back board *b* I apply means in the form of a sling, socket, or clip, by which the complete rest device can be hung from an umbrella handle, or a stick, or the like. In Figs. 1 and 2 I show a stick handle marked *A* carrying the complete rest device. For use with bent handles, such as shown in the drawings, I fit a V shaped piece of leather, fabric, or other flexible material *g* secured by narrow plates *g'* and screws *g''* to the back board *b* as is well shown in the drawings. This flexible sling *g* when opened out is well adapted to engage the stick or umbrella handle, and, after partly encircling the handle, can have its unattached extremity or free portion secured by a hook, or fastener, loop, or other simple means. The drawings show snap fastener halves *h*, *h'* and after engagement with the handle *A*, the lower female half of a fastener *h'* may be snapped over the top male fastener half *h*. In like manner the V shape string or loop when out of use can be held flat to the back board by snapping a fastener into engagement. When the complete desk or rest device is placed in position on a stick or the like, and the sling secured, said device is found to be most securely supported and will sustain a book, periodical, or the like, in a very good position for reading &c. The stick, umbrella or the like with the desk applied and the book in place can be supported by one hand with great comfort, thus leaving the other hand entirely free and unhampered. To suit straight handle sticks or umbrellas I may vary the form of sling or the like applied to the back board.

Figs. 4 to 6 show a slightly modified form of my desk or rest and as supported by an umbrella handle *A'*. In this form, the back-board *b* is shown provided with hinged extension pieces *j* pivoted at *j'* and these, when turned-up, enable the desk or rest to support a larger book. The extensions can be turned down to lie compactly against the back board as is obvious. The back board *b* is held down in the folded position by a spring snap *k* which engages the head of a screw *k'*.

In Figs. 7 and 8 I show a modified desk or rest device in so much that the ledge *d'* is hinged at *d'* and can fold down flat as indicated in Fig. 8. Also a spring wire is fitted at *l* with portions *l'* bent out at right angles in connection with the hinges, (see Fig. 8^a), whereby, when the turn-button *f''* is actuated to release the back board *b*, said back board opens or elevates itself automatically. The back board *b* is shown with the extension pieces *j*.

By the Figs. 9 and 10 I show the desk or

rest with a modified sling or socket which in this case consists of a flexible loop of leather *m* secured by narrow metal strips *m'* and screws *m''* to the back-board. The support in this case consists of a turned rod or pole *n* carried by a wooden cross base *n'*. The desk or rest can be adjusted to any required height and the sling *m* will readily hold the same in any adjusted position.

In Figs. 11 and 12 I show the back board *b* of my folding desk or rest with an applied back bracket *o* having a hole *o'* formed therein and with a spring *o''* let in in a recess and with an applied pinching screw *o''*. The desk or rest is shown carried upon a turned rod or support *p* which sockets in a cast-iron or other base *p'*. The desk or rest can be detached from the rod or support *p* and can be readily applied and any desired adjustment as to height made by means of the pinching screw *o''*.

In the Figs. 13 and 14 I show my desk or rest in another form, that is without a hinge between the boards *a* and *b*. The desk has the ledge *d* and the strip *f* and a bracket *o* with spring *o''* in a recess and a pinching screw *o''*. The desk or rest might well be carried on a rod or support *p* attached to a base similar to what I have before indicated.

My devices give great comfort for reading &c., whether on travel, outdoors, or at home.

I may cover the boards in parts or wholly with material and I may use a casing to contain the folded desk or rest. The folding desks or rests are so compact that same can be easily carried in the pocket.

I may make use of a handle or rod to take a hold on the stick, umbrella or stand employed to support my rest or desk and this may be provided with means to readily engage the stick, umbrella, or stand, and such modification is indicated in dotted lines at Fig. 7. My desk or rest devices are also a great convenience for writing or sketching. Being simple in construction my desk or rest devices can be put on the market at a low cost. The desk or rest devices may be made in wood, or in metal, or in any other suitable materials or from combinations of wood, metal or materials.

I declare that what I claim is:

1. In combination, a desk or rest having a back board, a supporting member secured to the back board, said member comprising a strip of flexible material having both of its ends fastened to said board and being adapted to embrace a stick or the like, and means for adjustably securing said strip to said board at a point intermediate the ends of said strip.

2. In combination, a desk or rest having a back board, a supporting member secured to the back board, said member comprising a

V-shaped strip of flexible material having both of its ends fastened to said board and being adapted to embrace a stick or the like, and means for adjustably securing said strip to said board at a point intermediate the ends of said strip.

In testimony whereof I have signed my

name to this specification in the presence of two subscribing witnesses.

JULIUS COHEN.
